UNITED STATES PATENT OFFICE.

ROYAL CORBIN, OF PLATTSBURG, NEW YORK.

ADDING-MACHINE.

SPECIFICATION forming part of Letter Patent No. 767,871, dated August 16, 1904.

Application filed April 20, 1904. Serial No. 204,032. (No model.)

To all whom it may concern:

Be it known that I, ROYAL CORBIN, a citizen of the United States, and a resident of Plattsburg, in the county of Clinton and State of New York, have invented a new and Improved Adding-Machine, of which the following is a full, clear, and exact description.

My invention relates to a simple construction of adding-machine capable of being held in one hand—the left hand, for instance—and which is conveniently and readily operated by a pencil or stylus held in the other hand to effect an addition of a column of figures and show the correct aggregate of each column added or to effect a reversal of the mechanism, thereby, for example, restoring the various dials quickly and accurately to their normal positions, at which time the zero on each of the dials will be presented to properly disposed openings in the casing of the device, at which openings the numerals are likewise presented at proper times which indicate the sum of the addition.

A further purpose of the invention is to provide an operative mechanism consisting practically of but three parts—a master unit wheel or dial and a wheel or dial representing tens and hundreds and a pawl for the combined tens and hundreds wheel or dial, which normally locks the latter wheel or dial and is operated at predetermined intervals by the rotation of the master unit wheel or dial as it releases the pawl from the combined tens and hundreds wheel or disk, acts upon the latter to turn it one point or numeral when the machine is operated for adding purposes, or wherein at any time both wheels or dials may be moved by the rotation of one in a backward direction to restore them to their normal or zero position.

Another purpose of the invention is to provide means whereby the master-wheel may be turned by the pencil or stylus exteriorly applied, so as to turn it and the master-wheel at proper time to effect the addition of succeeding numbers and present the total at the reading-face of the casing.

A further purpose of the invention is to provide such a construction of the device that the master-wheel may be controlled by the thumb

of the operator while the device is in operation.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a perspective view of the improved adding-machine, illustrating the manner in which it is designed to be held in the hand. Fig. 2 is a plan view of the improved adding-machine, the members being in their normal position, or in the same position as illustrated in Fig. 1. Fig. 3 is an edge view of the improved adding-machine, a part being in section to show more fully the construction of the casing. Fig. 4 is a plan view of the improved adding-machine, the parts being in the position shown in Figs. 1 and 2, the front or reading plate having been removed. Fig. 5 is an outer face view of the master units-wheel. Fig. 6 is a rear view of the same wheel, a portion of the cam at the back face thereof being shown broken away; and Fig. 7 is a vertical section taken practically on the line 7-7 of Fig. 6.

The casing A and, in fact, all of the parts are preferably made of metal and a metal which is as light as possible—for example, aluminium. The said casing consists of a rear plate α , a front or reading plate α' , and an interposed marginal supporting-rib α^2 . These plates are preferably more or less tapering at their sides, the lower portions of the body of the plates being narrower than the upper portions of their bodies, as illustrated in Figs. 1, 2, and 4. The rear plate α is provided at its upper edge with a central arched or segmental extension 10, which does not extend to the side edges of said plate, thus producing at the upper side portions of the plate horizontal shoulders 11 and 11 α . (Shown best in Fig. 4.) The marginal or spacing section α^2 extends around the marginal portion of the body of the back plate corresponding to the equivalent portion of the body of the front or reading plate α' , and at the upper right-

hand end of the spacing-section a^2 a lip 12 is formed, which extends beyond the right-hand shoulder 11^a, and the upper exposed inner edge portion of this lip is more or less concaved, so as to temporarily receive and hold a stylus or pencil which has been used in the operation of the device, as will be hereinafter particularly described.

The body portion of the front plate a' is provided at its upper edge with a projection 14, corresponding to the projection of the back plate and similarly located, thus providing upper shoulders 13 and 13^a at the side portions of the body corresponding to the shoulders 11 and 11^a of the back plate a ; but the segmental extension 14 of the front or reading plate a' is provided with an opening 15, preferably of circular construction, and this opening extends half-way within the body 20 of the said front plate a' and half-way within the said extension 14, as is shown in Figs. 1 and 2.

Above the opening 15 in the front face of the extension 14 from the front or reading body-plate a' a series of numerals 16 is produced, reading from the right in direction of the left, and the reading of the numerals is from "0" to "9," inclusive. The said numerals are spaced an equal distance apart, as is shown in Figs. 1 and 2.

Preferably just below the central portion of the opening 15 an aperture or side opening 17 is made in the front or reading plate a' of the casing A, and lower down a corresponding opening or aperture 18 is made, as is shown in Figs. 1 and 2. At these apertures or openings 17 and 18 the result of the addition is read. The circular opening 15 gives the thumb of the operator access to the outer surface of the master-wheel, so that said wheel is under perfect control.

The sections of the body A, just described, are connected by means of suitable screws 19 or their equivalents, which extend through the front or reading plate a' and through suitable apertures 19^a, formed in the spacing-section a^2 , and these screws 19 or equivalent devices employed are carried through the back plate a , as is shown in Fig. 3.

In connection with the casing A, I employ what I term a "master" units-wheel B and a wheel C, which expresses tens and hundreds. These wheels are located one below the other, the master units-wheel being the uppermost 55 wheel and overlapping the combined tens and hundreds wheel. The master units-wheel is provided with a series of numerals reading in a double sequence from "0" to "9," and the two ciphers in the arrangement of the numerals are opposite each other. These numerals are designated in the drawings by the reference-letter b .

At the center of the master units-wheel an opening 21 is made of circular formation 65 adapted to receive a stud 21^a, which stud ex-

tends outward and forward from the central portion of the circular opening 15 in the front section a' of the casing, as is particularly shown in Figs. 1 and 2. The units master-wheel B is adapted to turn loosely on this stud 7c 21^a, as is clearly indicated in the drawings. A series of teeth 20 in the nature of ratchet-teeth are formed at the periphery of the master units-wheel B, and these teeth are so grouped that one will be practically opposite 75 each numeral on the said wheel, the numerals appearing only on the front face of the wheel. The teeth will incline from the right in direction of the left of the said wheel, and their left-hand edges are more or less straight. 80

A disk 22 is secured to the back portion of the master units-wheel at its central portion, and this disk is provided with a central opening 21^b, which is in registry with the opening 21 in the master-wheel proper. The disk 22 is of much less diameter than the diameter of the master-wheel B and, as is shown in Fig. 6, is provided with opposite recesses 23 and 24, the barrier or transverse walls of which recesses are oppositely located, as is also 90 shown in Fig. 6. This disk 22 may be termed a "cam-disk," as the said disk, in connection with a pawl to be mentioned, regulates the movement of the combined tens and hundreds disk or wheel C. 95

The disk 22 is secured to the master-wheel B, preferably by means of suitable rivets 25, although other means may be employed for the purpose, and between the cam-disk 22 and the master units-wheel B, I locate usually a 100 strip 26 of metal apertured to correspond to the apertures 21 and 21^b in the wheel B and its disk 22, and the ends 27 of this strip extend beyond the cam-disk 22, and such ends are contracted and are in the form of teeth, 105 being located between the respective numerals "9" and "0" on the master units-wheel, but at the back thereof, as has been stated.

The combined tens and hundreds wheel C is mounted to turn on a stud 28, which is below the periphery of the master units-wheel B, and this combined tens and hundreds wheel C is flat, so that when in position on the stud 28 the peripheral portion of the master units-wheel will pass over its front face. 115

On the front face of the combined tens and units wheel C numerals c are produced, reading consecutively from "0" to "19," inclusive, and the said combined tens and hundreds wheel C is provided with peripheral teeth 29, 120 more or less triangular. A tooth 29 is opposite each numeral on the wheel, the numerals being produced near the peripheral portion of the wheel, as is shown in Fig. 4.

A pawl 30 is employed to coact with the teeth of the wheels B and C, and this pawl between its center and its upper end is mounted to turn on a stud 31 at the right-hand side of the pivot of the master units-wheel, and the stud 31 is secured to the back body-plate 130

a of the casing, as is shown in Fig. 4. The upper portion of the pawl 30 is inclined in direction of the cam-disk 22 and is provided with a head 30^a, adapted to engage with the 5 peripheral portion of the said cam-disk, while the lower and longer member of the pawl 30 is provided with a head 30^b, adapted to engage with the toothed peripheral surface of the combined tens and units wheel C, so as to 10 enter the spaces between the said teeth and prevent the latter wheel from shifting from its set position.

The numerals on the master units-wheel appear at the opening 17 in the front plate *a'* of the casing, while the numerals on the combined tens and units wheel C appear at the 15 lower opening 18, also produced in the front plate of the casing. Prior to the use of the machine, or in the normal position of the two 20 wheels B and C, a cipher will appear at both of the openings 17 and 18, as is illustrated.

An opening 32 is produced in the master units-wheel B, removed a desired distance from its center, and this opening 32 extends 25 through the said wheel and its attached parts from one face to the other and is of such size as to readily receive the end of a pencil or stylus of any suitable description.

In the operation of this adding-machine, the 30 wheels having been properly set by turning the master units-wheel to the left, so as to bring a cipher at the opening 17 and through the connection of said master-wheel with the combined tens and hundreds wheel C causing 35 at the same time a cipher to appear at the lower opening 18, if it is desired to add five to seven, the device being held in the left hand, as shown in Fig. 1, it is simply necessary to place the stylus or pencil in the space 40 between two teeth on the master or units wheel B adjacent to the figure "5," which is on the front scale 16 of the front of the casing, and then the pencil or stylus is forced to the right, revolving the master-wheel five 45 points, and when such revolution has been made the pencil or stylus will strike the left-hand shoulder 13^a and will be prevented from accidentally slipping from the shoulder by means of the projection or horn 12, heretofore 50 referred to and forming a portion of the spacing-strip *a'* of the casing. Next the stylus or pencil is placed in the space between the two teeth of the master-wheel adjacent to the numeral "7," and then the master-wheel is again 55 revolved to the right through the medium of the pencil or stylus until the pencil or stylus shall have reached the right-hand shoulder 13^a on the casing and will be again prevented from slipping therefrom by the horn or projection 12. When the master units-wheel was 60 first revolved, the numeral "5" was rendered visible at the opening 17; but after the second partial revolution of the master units-wheel the figure "2" will appear at the upper opening 17 and the numeral "1" at the lower

opening 18, reading "12," which is the sum of seven and five, the numeral "1" being on the lower wheel C and the "2" on the master-wheel B.

It will be observed, as stated, that there are 70 two series of numerals on the master units-wheel, reading each from "0" to "9," inclusive, whereas the combined tens and hundreds wheel C has produced thereon numerals reading from "0" to "19," inclusive, and at each 75 half-revolution of the master units-wheel B the combined tens and hundreds wheel C is turned one tooth. This is accomplished in the following manner: When one-half of the revolution of the master units-wheel B has 80 been made, the upper head 30^a of the pawl 30 will be opposite one or the other of the depressions 23 and 24 in the cam-disk 22. Consequently the lower head 30^b of the said pawl is free to pass out from its position between adjacent teeth in the lower or combined tens and hundreds wheel C, and just at this time one point 27, extending at the rear of the master units-wheel, will enter the space between adjacent teeth of the wheel C, presented to it, as is shown by dotted lines in 85 Fig. 4, and will consequently move the said wheel C the distance of one tooth, and at that time the upper head 30^a of the pawl 30 will have ridden out of the recess or depression 90 in which it was located to the plain peripheral portion of the cam-disk 22, thereby forcing the lower head 30^b into the most convenient space between opposing teeth on the lower wheel C, preventing the latter wheel from 95 moving until the upper or master units-wheel has again made a half-revolution.

It will be understood that the master units-wheel B must be turned a certain number of times to bring the cipher on the disk C at the 100 opening in the casing after an addition has been made—as, for example, if the disk C stood at "16" in order to reset both disks to zero the master units-wheels would have to be turned eight times; but it will be understood 105 that the gear connections between the disk C and the master units-wheel B may be so made as to accomplish the aforesaid result without so many turns of the master units-wheel.

This device is exceedingly simple in its construction. It comprises but few parts and is absolutely perfect with reference to calculation. It can be readily and quickly manipulated, in fact as rapidly as numbers can be read by or dictated to a person controlling the 110 device.

Having thus described my invention, I claim as new and desire to secure by Letters Patent—

1. In adding-machines, a casing having an upper segmental section and a shoulder at each 115 side of said section, a master units-wheel mounted to revolve within the casing and having its central portion exposed for contact by the thumb of the operator, a combined tens and hundreds wheel likewise mounted to 120

revolve in the casing, each wheel being provided with numerals upon its reading-face, and peripheral teeth corresponding in number and practically in location to the said numerals, the peripheral teeth of the master units-wheel extending beyond the upper segmental section of the casing and being visible at the said shoulders, a pawl adapted for normal engagement with the combined tens and hundreds wheel and released from said engagement by the master-wheel at a point in its revolution, the said master units-wheel being provided with an inner point which at the time of such release engages with the combined tens and hundreds wheel to move the latter one numeral.

2. In an adding-machine, a casing, a master units-wheel mounted to revolve in the casing and having a portion of its periphery exposed, the master units-wheel being provided with numerals on its outer face reading from "0" to "9" inclusive, and a point on its outer face located between the numerals "0" and "9," a cam-disk located on the rear face of the master units-wheel having a recess therein, a combined tens and hundreds wheel also mounted to revolve in the casing and having a series of numerals thereon, teeth at the periphery of both wheels, located opposite the numerals thereon, and a pawl pivoted in the casing, having engagement with the said cam-disk and with the toothed periphery of the combined tens and hundreds wheel, the said master units-wheel being provided with an opening therein at one side of its center, adapted to receive a stylus or pencil, whereby the said wheel may be revolved in one direction, the same stylus or pencil being adapted for engagement with the teeth of the said master units-wheel to turn it in an operative or working position, and shoulders formed on the upper portion of the said casing, limiting the movement of the stylus or pencil when in operative engagement with the said master units-wheel, as described.

3. In an adding-machine, a casing, a combined tens and units wheel mounted to revolve

in the casing, having numerals upon its outer face reading from "0" to "9" inclusive and provided with peripheral teeth corresponding in number to the numerals, a master units-wheel also mounted to revolve within the casing, having a portion of its periphery exposed at the upper portion of the casing, the casing being provided with shoulders at each side of the exposed portion of said master units-wheel, the master units-wheel being provided with an opening at one side of its center to receive a stylus or pencil to impart movement thereto in one direction, and with a series of inclined peripheral teeth, together with numerals reading in two series, each from "0" to "9" inclusive, the teeth on the periphery of the master-wheel corresponding in number to the numerals thereon, and a cam-disk located at the rear of said master units-wheel, having opposing recesses in its periphery and points extending from the back of the cam-disk in a radial direction, the points being located so as to be opposite the space between the numerals "0" and "9," and a pawl having an upper and a lower head, which pawl is pivoted in the casing, the upper head riding on the periphery of said cam-disk and the lower head being in engagement with the periphery of the combined tens and hundreds wheel, said casing being provided with a main opening in its front, exposing the opening in the master-wheel, and with a lower side opening adapted to expose the numerals on the two wheels, together with a scale reading from "0" to "9" at the upper portion of the main opening, the spacing of the numerals on the scale corresponding to the spacing of the peripheral teeth on the master-wheel, as set forth.

In testimony whereof I have signed my name to this specification in the presence of two subscribing witnesses.

ROYAL CORBIN.
